MOTOR DRIVEN SPROCKET ACTUATED MACHINE WRENCH

Edward J. Roberts, Hampton, Va.

Application February 18, 1957, Serial No. 640,883

2 Claims. (Cl. 81—57)

This invention relates to machine tools and more particularly to a wrench for use on freight class types of locomotives.

It is an object of the present invention to provide a wrench for slackening off and taking up on the brake adjusting screw of locomotive brake shoes.

It is another object of the present invention to provide an automatic wrench of the above type for removing the brake shoes of various types of locomotives efficiently and effectively with a minimum amount of manual labor.

Other objects of the invention are to provide an automatic wrench bearing the above objects in mind which is of simple construction, has a minimum number of parts, is inexpensive to manufacture and efficient in operation.

For other objects and for better understanding of the invention, reference may be had to the following detailed description taken in conjunction with the accompanying drawing, in which:

Figure 1 is a side elevational view, with parts broken away, of an automatic wrench made in accordance with the present invention;

Figure 2 is a top plan view of the device shown in Figure 1;

Figure 3 is an enlarged cross sectional view taken along line 3—3 of Figure 2; and

Figure 4 is an enlarged cross sectional view taken along line 4—4 of Figure 2.

Referring now to Figure 1 of the drawing, an automatic wrench made in accordance with the present invention is shown to include a substantially rigid base frame 10 that is supported in a horizontal position upon a pair of downwardly diverging adjustable legs 12 at one end and a downwardly depending single leg 13 at the opposite end. A housing 15 having an upwardly extending carrying handle 11 is integrally secured to the base frame 10 and includes a longitudinally extending shield 17.

As is more clearly shown in Figure 3, the shield 17 is provided with a pair of oppositely and outwardly extending circular flanges 19 that rotatably support a sprocket wheel 20. This sprocket wheel 20 has a plurality of sprocket teeth 23 and defines a central hexagonal opening 22 that is adapted to removably receive the nut or bolt head of a locomotive device. A sprocket chain 25 is trained about the sprocket wheel 20 at one end and is in driven engagement with a drive sprocket 26 at the opposite end. The drive sprocket is secured to a rotatable shaft 27 that has a bevel gear 27 secured at one end. An intermediate idler shaft 30 has a bevel gear 29 at one end in meshing engagement with the bevel gear 28 upon the sprocket shaft and another bevel gear 31 at the opposite end in meshing engagement with a similar bevel gear 33 secured to the rotor shaft 34 of the rotor 35 of a pneumatic motor 36.

The pneumatic drive motor 36 is supplied with pres-

2

sure fluid through a supply line 40 and directional control valves 41, 42, that control the direction of rotation of the rotor 35. A connecting link 43 is operatively secured to both valves 41, 42, so as to synchronize their movement, in response to actuation of the operating handle 44.

Thus, in operation, the nut to be driven is engaged by the driven sprocket 20, whereupon the operating handle 44 is moved so as to open the associated valves 41, 42, so that fluid enters the motor housing 36 to drive the rotor 35 in a predetermined direction, depending upon whether the nut is to be tightened or loosened. Rotation of the rotor 35 is operative to effect rotation of the sprocket 26 which in turn, drives the sprocket wheel 20 through the sprocket chain 25. All of the legs are adjustable so as to permit the device to be used on various types of equipment, and is provided with the carrying handle 11 so as to facilitate the adjustment thereof.

While various changes may be made in the detail construction, it shall be understood that such changes shall be within the spirit and scope of the present invention as defined by the appended claims.

What I claim as new and desire to protect by Letters Patent of the United States is:

- 25 1. A motor operated gearing controlled wrench for driving nuts comprising, in combination, a base frame having a pair of spaced parallel guard plates, a circular opening in each one of said guard plates, a circular flange extending outwardly from the opening defining portions 30 of each of said circular openings defining circular bearings, a driven sprocket wheel having a centrally located nut socket with outwardly extending shoulders in rotatable engagement with said circular flanges, a driving sprocket wheel, a sprocket chain drivingly connecting said driving sprocket wheel to said driven sprocket wheel, and a pneumatic motor supported upon said base frame in driving engagement with said driving sprocket wheel, adjustable support means for said base frame including a pair of downwardly diverging legs at one longitudinal end 40 of said frame and a downwardly extending leg at the opposite longitudinal end of said frame, said driven sprocket wheel and said driving sprocket wheel together with said pneumatic motor being mounted in spaced longitudinal alignment upon said base frame, said pneumatic motor comprising pneumatic supply means, a valve for supplying pneumatic pressure from said supply means to drive said motor in one direction, a valve for supplying pneumatic pressure from said supply means to drive said motor in a reverse direction, linkage connecting said valves for selectively controlling the direction of flow to said motor, and bevel gears drivingly connecting said motor to said driving sprocket.

- 55 2. The combination according to claim 1, wherein said linkage is operative to simultaneously operate both of said valves to drive said motor in either direction in response to actuation of said linkage in a single predetermined direction.
